SURFACE ORNAMENTING MACHINE

Nicholas G. Koppinger, St. Clair Shores, Mich.,
assignor to Briggs Manufacturing Company,
Detroit, Mich., a corporation of Michigan

Original application July 19, 1939, Serial No.
285,373. Divided and this application February
28, 1942, Serial No. 432,752

10. Claims. (Cl. 101—154)

This invention relates to surface ornamenting or decorating machines, and more particularly to machines for applying surface ornamentations such as a wood graining finish to curved metal surfaces such, for instance, as metal moldings for windows of motor vehicle bodies. The present application is a division of my copending application Patent No. 2,280,413, April 21, 1942.

One of the objects of the present invention is to provide a surface ornamenting or decorating machine which can apply a desired design or ornamentation to a curved surface without distorting such design, particularly in places where the curvature of the surface changes at an increased rate such, for instance, as in corners.

Another object of the invention is to provide a machine of the character specified in the preceding paragraph, which enables applying the desired ornamentation economically and at a rate acceptable for quantity production.

Still another object of the invention is to provide a surface decorating machine which may be easily and safely operated by an unskilled worker.

A further object of the invention is to provide a surface ornamenting machine adapted to apply an ornamentation of a desired design to a surface and including improved means adapted to vary adjustably the character of such design to make it selectively more light or heavy.

A still further object of the invention is to provide a surface ornamenting machine having an inking roller, in which machine improved means are provided to permit adjustments for varying the amount of paint or printing ink received by said roller for transfer to the belt.

A still further object of the invention is to provide a surface decorating machine having a transfer belt and an inking roller, means being provided to control the amount of ink actually transferred from the roller to said belt.

It is an added object of the present invention to provide an improved surface decorating machine of the foregoing character, which machine is relatively simple in construction, safe and dependable in operation, has a high production capacity, and is relatively inexpensive to manufacture and service.

Other objects of this invention will appear in the following description and appended claims, reference being had to the accompanying drawings forming a part of this specification wherein like reference characters designate corresponding parts in the several views.

Fig. 1 is a perspective view of the machine em-

bodying the present invention, the workpiece being shown therein in the printing position.

Fig. 2 is an end view illustrating on an enlarged scale the design roller and the improved inking means therefor.

Fig. 3 is a fragmentary side view illustrating the design roller and the improved scraping and ink regulating means therefor.

Fig. 4 is a perspective view of the upper portion of the machine viewed from the front left-hand corner thereof.

Fig. 5 is a rear elevation of the machine.

Before explaining in detail the present invention it is to be understood that the invention is not limited in its application to the details of construction and arrangement of parts illustrated in the accompanying drawings, since the invention is capable of other embodiments and of being practiced or carried out in various ways.

20 Also it is to be understood that the phraseology or terminology employed herein is for the purpose of description and not of limitation.

In the drawings there is shown, by way of example, a surface decorating or ornamenting machine embodying the present invention. The machine illustrated in the drawings and herein-after described is constructed especially for applying surface ornamentation to automobile window moldings, which ornamentation is usually in the form of a wood grain finish. It will be understood, however, that the machines embodying the present invention are not limited for the above use and may be successfully used for applying ornamentations to other articles or work-pieces, particularly those having curved or irregular surfaces.

30 Referring to the drawings and particularly to Fig. 1, the machine illustrated therein comprises generally a base 20 preferably of a circular form, in which base there is affixed an up-standing standard 21 which serves as a main frame or skeleton member on which the entire machine is assembled. To the upper end of said standard 21 there is secured in any suitable manner a ring or eyelet 22 by which the entire machine may be raised with the use of a crane for transporting the machine about the plant.

40 The operative mechanisms of the machine may be divided structurally into three parts in accordance with the way in which they are mounted; the upper portion including the drive, the design or inking roller and the driving pulley for the transfer belt; the lower portion including 45 the form roller, the work supporting table and

55 the form roller, the work supporting table and

the associated mechanisms; and the pedal mechanism mounted on the base 20.

The upper portion comprises a sleeve 23 fitting on the standard 21, which sleeve is split for a portion of its length and may be drawn together with the aid of a suitable screw to grasp the standard and thus to be set at any desired position on the standard for raising or lowering of the transfer belt 30. The mechanisms comprised by the lower portion are assembled on a sleeve 31 set permanently on the standard 21 for a definite type of work.

The upper portion of the machine comprises generally a pulley for driving the transfer belt, an inking or design roller for transferring the printing ink of a predetermined pattern to the transfer belt, means for supplying ink to the inking roller, and scraper means for removing the excess ink from the inking roller, as well as scraper means for cleaning the transfer belt. The upper portion of the machine also carries means for driving said pulley, the inking roller and the ink supplying means. The lower portion includes a form roller or idler pulley over which the transfer belt passes, which pulley or roller generally conforms to the cross sectional shape of the molding; a swinging table for supporting the molding in its operative position; guide rollers for guiding the workpiece during the printing operation and maintaining the contact between said workpiece and the transfer belt; and means for locking the swinging table in the supporting position. On the base 20 there is mounted the pedal 33 which operates the mechanisms carried by said lower portion.

Referring now more particularly to the drawings, there is provided on the upper sleeve 23 a platform 35 on which there is mounted an electric motor 36 drivingly connected by means of a suitable belt 37 with a speed reducing box 38 of any suitable construction. On the continuation of the shaft 39 of the speed reducing box there is mounted a driving pulley 40. The shaft of the speed reducing box is connected by means of a train of gears, the last gear whereof is indicated in dotted lines in Fig. 2, with the shaft of the inking or design roller 41. I prefer to have the driving pulley 40 and the inking roller 41 operate at the same rotative speed. In order to prevent slippage of the belt 30 at the inking roller 41, the sizes of the driving pulley and the inking roller have to be properly selected. I prefer to have an inking roller which has a radius equal substantially to the sum of the radius of the driving pulley 40 plus the thickness of the belt. A small correction of the above geometric calculation may be necessary in order to provide for slight compression of the transfer belt between the inking roller 41 and a pressure roller 42, as well as for the slight stretching of the relatively heavy belt 30 due to the centrifugal force of operation.

The inking or design roller 41 is in the form of a cylinder, on the outside surface whereof there is provided the desired pattern or design. Good results are attained with the use of copper inking rollers having a pattern or image provided on the surface thereof by the well known photo-engraving process commonly used in the art of printing. In this case a wooden board of the corresponding size is first finished to show its grain and is thereupon photographed for the purpose of producing the image on the inking roller. In order to prevent rapid wearing out of the engraved copper surface of the inking roller 41,

it is chromium plated to provide a better wearing surface. The image or design on the roller 41 is produced by minute depressions or indentations of varying sizes, which depressions retain the printing ink. When a relatively soft belt comes in contact with the surface, the ink retained in said depressions is partly transferred onto the surface of the belt.

Means for supplying ink to the design roller 10 comprise, in the present embodiment, a rotary pump 43, driven by a shaft of which the shaft 15 of the inking roller 41 is a continuation. The intake side of the pump is connected by means of a pipe 44 composed of a plurality of sections 15 to produce proper turns, with a reservoir 45 which serves as both an overflow and a supply reservoir. The discharge side of the pump 43 is provided with a pipe connection 46 having a discharge nozzle 47 adapted to discharge the ink 20 in a thin wide stream onto the surface of the rotating inking roller 41.

The ink delivered by the discharge nozzle 47 covers the surface of the inking roller completely, and being of a certain density it forms on the 25 surface of the inking roller a layer of a considerable thickness. Therefore, means are provided to scrape off the excess paint from the surface of the inking roller and to leave the ink only in the above mentioned depressions or indentations.

30 In the present embodiment the scraping means are in the form of a thin blade 50 secured in a shaft 51 journaled in a bracket 52. The bracket 52 is secured by means of screws 53 to the extension provided on the sleeve 23, the holes in said 35 bracket 52 being larger than is necessary for the passage of the shanks of the screws 53. The shaft 51 extends through the lower end of the bracket 52 and a bent rod 54 is secured by means of a collar to the projecting end of the shaft 51, 40 as is best shown in Figs. 2 and 3. The rod 54 has a portion extending vertically from the scraper shaft, and thence the rod is bent to provide a lateral extension having a weight 55 adjustably mounted on its end which tends to rotate the blade in the direction to press said blade against the surface of the inking roller. As the roller rotates, the scraper blade 50 scrapes off the ink from the surface thereof leaving the ink in the pattern indentations only. By virtue 45 of the provision of the adjustable bracket 52 the scraper blade may be moved toward and away from the inking roller 41 changing the angle at which the scraper blade 50 contacts the surface of the inking roller. Changing this angle enables varying the quantity of ink which is left on the inking roller and, therefore, it enables transferring more or less ink to the transfer belt 30, thereby making the character of the design transfer to the workpiece adjustable, i. e. either 50 heavier or lighter as the circumstances may require. The blade 50 may also be moved with the aid of the adjustments of the bracket 52 to give uniform pressure on the roller 51 along the entire length of the blade 50. This feature is 55 very important, since in some prior structures of this general character there was no means for adjusting the blade to correct the design which would come out heavier on one side.

The pressure roller 42 is swingingly mounted on 70 the bracket 56 adjustable with respect to the roller 41 by means of a screw 57. The bracket 56 carries a screw 58 serving as a hinge for a bent arm 59 one end of which carries the pressure roller 42 while on the other end there is provided 75 an adjustable weight 60, see Fig. 1. By moving

the weight 60 toward or away from the hinge 58 the pressure which the roller 42 exerts on the belt 30 may be adjustably varied. Changing this pressure varies the amount of ink which is transferred to the belt 30 which, in turn, tends to produce heavier or lighter design on the workpiece. Thus, second design adjustment means are provided in my improved machine. In the case when lighter design is produced on the workpiece, more untransferred ink is left on the transfer belt 30 and, therefore, it is necessary to have means which remove the ink left on the transfer belt 30 after it contacts the workpiece and before it comes in contact with the inking roller 41 for receiving a new impression. Said means are exemplified in the present embodiment of the invention by a scraper 61 which is best shown in Fig. 1. The scraper 61 is mounted similarly to the scraper 50 and is provided with an adjustable weight 62 serving the purpose similar to that of the weight 55. The amount of ink which is removed by the scraper 61 is relatively small and it may be wiped from the scraper 61 from time to time. It may be advisable to provide a small container under the scraper 61 if light designs are produced by the machine most of the time. For cleaning the sides of the belt 30 there are provided side scrapers 66 best shown in Fig. 1.

A switch box 63 is also mounted on the upper portion of the machine, which box is provided with a plug connection 64 for connecting the machine with a source of electric current for operating the motor 36.

The lower portion of the machine is mounted on the sleeve 31 as mentioned. Said lower portion comprises an idler pulley or form roller generally indicated by the numeral 70 which is mounted on a shaft 71 floatingly journalled in a bracket 72 provided on the sleeve 31. The roller 70 is of a laminated construction and is shaped to the general form of the cross section of the workpiece. The belt 30 is passed over the driving roller 40 and the form roller 70. The belt 30 is of a type generally used in printing work. It comprises generally a base made of a material capable of sustaining the upper layer of a glue and gelatin composition providing a smooth pigment-receiving surface.

A swinging table 13 is hingedly mounted on the lower sleeve 31, said table being provided for easy manual operating with counterbalancing means including a weight 79, said weight tending to maintain the table 13 in its raised position. External means operated with the aid of the pedal 33 are provided for bringing the table 13 into its lower or loading position.

There are also provided means for locking the table 13 in said lower position, unlocking thereof being done by manipulating the pedal 33. The pedal 33 is also used to operate the guide rollers 81 provided with grooves receiving the edge of a workpiece 80 and effecting actual contact of said workpiece and the transfer belt 30. In operation, with the belt 30 being driven from the motor 36, the workpiece 80 is manipulated manually and is moved around past the transfer belt 30 at the form roller 70 until the entire length of the workpiece 80 is printed upon.

When the printing operation is completed, the operator lowers the table by continued pressure on the pedal 33. When the pedal is locked in its lowermost position, which is done automatically, the decorated workpiece is removed from the

machine and a new one is inserted therewith in a similar manner.

The construction of the lower portion of the machine does not of itself form a part of the present invention, and therefore, no more detailed description thereof as well as other structural features of the machine is deemed necessary here, the same being described in detail in my said copending application Patent No. 2,280,413, April 21, 1942, of which the present application is a division.

There is thus provided an improved surface decorating machine including a transfer member or belt and an improved roller with improved ink scraping and belt pressing means therefor, whereby ink transferring function of said roller is regulated to give the desired character of printed design. Thus, the objects of the present invention listed above and numerous additional advantages are attained.

I claim:

1. In a surface ornamenting machine, a transfer belt extending continuously over two pulleys and having substantially parallel courses therebetween, an inking roller operatively mounted adjacent said belt and adapted to engage the same at the working surface thereof intermediate said pulleys, a pressure roller operatively mounted between said pulleys and said belt courses and adapted to engage said belt from the non-working surface thereof and to press said belt against said inking roller, and means for adjustably varying the pressure of said pressure roller on said inking roller in order to vary adjustably the amount of ink transferred to said belt.

2. In a surface ornamenting machine, a transfer belt operatively arranged over two pulleys, an inking roller operatively mounted adjacent said belt and adapted to engage the same at the working surface thereof intermediate said pulleys, a pressure roller operatively mounted between said pulleys and adapted to engage said belt from the non-working surface thereof and to press said belt against said inking roller, and means for adjustably varying the pressure of said pressure roller on said inking roller in order to vary adjustably the amount of ink transferred to said belt.

3. In a surface ornamenting machine, a driving pulley and a form pulley, a transfer belt operatively arranged over said pulleys, an inking roller adapted to transfer ink in a desired pattern to said transfer belt at a point intermediate said pulleys, and a positive driving connection between said driving pulley and said inking roller.

4. In a surface ornamenting machine, a driving pulley and a form pulley, a transfer belt operatively arranged over said pulleys, an inking roller adapted to transfer ink in a desired pattern to said transfer belt, and a positive driving connection between said driving pulley and said inking roller, said driving pulley having a radius which is smaller than the radius of said inking roller substantially by the thickness of said transfer belt.

5. In a surface ornamenting machine, a driving pulley, an idler pulley spaced therefrom, a transfer belt extending continuously around said pulleys and connecting the same, an inking roller arranged to contact said belt at a point intermediate said pulleys, and means for driving said driving pulley and inking roller at the same speed, the respective radii of said driving pulley

and inking roller being such that the linear speed of travel of the belt is substantially the same as the peripheral speed of travel of the roller.

6. In a surface ornamenting machine, a driving pulley, an idler pulley spaced therefrom, a transfer belt extending continuously around said pulleys and connecting the same, an inking roller arranged to contact said belt at a point intermediate said pulleys, and means for rotating said driving pulley and inking roller at the same speed, the radius of the driving pulley being less than the radius of the inking roller by substantially the thickness of said belt.

7. In a surface ornamenting machine, a transfer belt operatively arranged over two pulleys and having vertically extending substantially parallel courses between said pulleys, an inking roller operatively mounted adjacent said belt and adapted to engage the same at the working surface thereof intermediate said pulleys, a pressure roller operatively mounted between the courses of said belt opposite said inking roller and adapted to engage said belt from the non-working surface thereof and to press said belt against said inking roller.

8. In a surface ornamenting machine, a transfer belt extending continuously over two pulleys and having substantially parallel courses therebetween, an inking roller operatively mounted adjacent said belt and adapted to engage the same at the working surface thereof intermediate said pulleys, a pressure roller operatively mounted between said pulleys and said belt

courses and adapted to engage said belt from the non-working surface thereof and to press said belt against said inking roller, and an adjustable counterweight varying the pressure of said pressure roller on said inking roller in order to vary adjustably the amount of ink transferred to said belt.

9. In a surface ornamenting machine, a transfer belt operatively arranged over two pulleys and having substantially parallel courses between said pulleys, an inking roller operatively mounted adjacent said belt and adapted to engage the same at the working surface thereof intermediate said pulleys, a pressure roller operatively mounted between the courses of said belt opposite said inking roller and adapted to engage said belt from the non-working surface thereof and to press said belt against said inking roller.

10. In a surface ornamenting machine, a transfer belt, an inking roller arranged to contact the working surface of said belt and to transfer ink thereto, a scraper blade cooperable with said roller, a supporting bracket, a rock shaft extending through said bracket, said blade being mounted on said shaft at one side of the bracket, a rod connected directly to said shaft at the opposite side of said bracket, a counterweight carried by said rod, and means for adjusting the position of said bracket to position the shaft and said blade nearer or further from said roller, said rod and counterweight being adjustable as to position bodily with said bracket.

NICHOLAS G. KOPPINGER.
